Filed Mar. 12, 1968, Ser. No. 10,937

Term of patent 14 years

Int. Cl. D6—01

U.S. Cl. D15—8

FIG. 1.

FIG. 2.

FIG. 3.

FIG. 4

FIGURE 1 is a top plan view of a portable seat for use by a cable splicer showing my new design;

FIGURE 2 is a right side elevation;

FIGURE 3 is a bottom plan view; and

FIGURE 4 is a rear end elevation, portions of the inclined leg of the mounting bracket visible in FIGURE 2 having been broken away due to space limitations.

The side not shown in FIGURE 2 is a mirror image of the side shown.

I claim:

The ornamental design for a portable seat for use by a cable splicer, as shown and described.
